UNITED STATES PATENT OFFICE

LUCIEN LOUIS JOSEPH PROMPT, OF COLOMBES, FRANCE

PRESSURE PRODUCING MEANS

Application filed June 24, 1929, Serial No. 373,432, and in France July 4, 1928.

The present invention relates to pressure producing means and has essentially for its object to provide a device adapted to exercise a uniform and simultaneous pressure at several points of a given surface, whereas the pressing effort is locally applied.

The said apparatus is chiefly characterized by the fact that it comprises a row of balls, rollers or the like, in contact with one another, which are parallel with the surface to be pressed and are guided in a direction parallel with said surface and certain of the said elements, regularly spaced, are set out with reference to the others in the direction of the pressing movement to be produced, and are in contact with the movable pressing member, a suitable controlling element being employed to bring said elements into mutual contact for pressing purposes.

20 Further characteristics of the invention will be specified in the following description.

In the accompanying drawings, which is given solely by way of example, Figs. 1 and 2 represent an application of the pressure producing means according to the invention, and Figs. 6 and 7 show another particular application of said pressure means for the end-to-end coupling of hoses.

Fig. 1 shows a vertical section on the line A—C of Fig. 2.

Fig. 2 is a horizontal section on the line D—D of Fig. 1.

Fig. 3 is a diametrical lengthwise section of a coupling device according to the invention.

Fig. 4 is a bottom view of the same.

Fig. 5 is a horizontal section on the line 5—5 of Fig. 3.

Fig. 6 is a bottom view of a modification of the securing casing in which is slidable the coupling member mounted on one of the pieces of hose.

Fig. 7 is a top view of the corresponding coupling member, mounted on the other piece of hose.

Fig. 8 is an elevational view of a modification of the coupling device.

Fig. 9 is a plan view of the lower half of the device shown in Fig. 8.

50 In the embodiment illustrated in Figs. 1

and 2, the pressure producing means according to the invention is used to exercise a pressure uniformly distributed upon the circumference of a disk-shaped packing member or diaphragm 1 interposed in a conduit A as a fluid-tight partition adapted to burst when the pressure prevailing in the conduit on one of its faces exceeds a predetermined value. In practice, arrangements of this kind are used for instance for the cleaning of boilers. 55 The use of the pressure producing means according to the invention allows of a rapid removal of the diaphragm. The diaphragm 1 is disposed between two blocks 2 and 3. Upon the block 2 is caused to bear, against 60 the pressure of reaction springs 4, a flanged sleeve 5 which is vertically slidable in two upper superposed members 6 and 7, the member 7 resting upon the lower block 3. The members 2 and 5 are provided with bores 65 extending throughout and coaxial with the conduit A. The members 3, 6 and 7 are rigidly connected together and with flanges A¹—A² of the conduit A by means of bolts B.

In the plane of their contact surface 8, the members 6—7 are provided with respective annular grooves 9—9^a, and these when superposed will form an annular recess in which balls 10 are movable.

The lower member 7 is pierced at suitable 80 points, and in coincidence with said groove 9^a, with curved apertures 11 (Fig. 1) in which are movable, according to a circular arc, respective balls 12 whose radius is optionally the same as that of the balls 10, and said balls 12 85 rest upon the slidable member 5. The vertical dimensions of the members 6 and 7 are such that in the idle position, the vertical distance l between the centres of the balls 10 and 12 is less than the sum of the radii, so that the motion of the upper balls 10 in the said recess 9—9^a is limited, since the said balls make contact with the lower balls 12.

The lower balls 12—12^a—12^b—12^c—12^d 90 are distributed uniformly about the circle whose centre is O (Fig. 2) and they divide the balls 10 into various sets whereof each comprises a certain number of balls (three in the present example). The left hand set (Fig. 2) comprises only two balls 10^a and 10^b.

10^b, between which is engaged the head 18, of spherical, ovoid or other form, of a screw 14 having a square or hexagonal outer end 15, on which may be mounted a lever, hand 5 wheel or other controlling member.

The operation is as follows:

The motion of the said screw 14 in the direction of the arrow (Fig. 2) tends to force apart the balls 10^a and 10^b, and due to its 10 special form, the head 13 exercises a lateral pressure thereon; the said balls bear against the member 6 and against the walls of the slot 9—9^a, thus pushing the balls 12—12^a both downwardly and laterally, and these latter 15 are thus brought against the balls 10^a—10^b of the two succeeding upper sets. The balls 10^a—10^b will in turn push the following balls, and so on, as far as the ball 10^e which will not be moved.

20 In this manner the lower balls will receive a downward thrust which they impart to the member 5 which thus presses the disk 1 between the blocks 2 and 3. The load applied by the screw 14 upon the balls 10^a and 10^b 25 will thus be entirely distributed upon all of the lower balls, since each of these balls can only press upon the member 5 by using as a fulcrum the adjacent lower ball 12, through the medium of the upper balls 10 of the set 30 which connects them together. The motion thus produced between the lower balls 12 is entirely of a differential nature, and it assures the integral and automatic distribution of the pressure of the screw upon all points of 35 the disk 1.

Obviously, the invention is not limited to the form of construction herein described and represented, which is given solely by way of example. The apparatus may be placed in 40 any position, whether vertically or horizontally, etc. The screw 14 may be disposed vertically or in any other position, and it may be replaced by a ball and a pressure rod or stud, or by a pressure rod alone, which is 45 subject to suitable control such as mechanical, electrical, pneumatic or hydraulic. In a more general manner, it may be replaced by a member of any suitable form adapted to separate the balls 10^a and 10^b.

50 The ball 10^b may be made stationary, and the pressure of the screw may be brought solely upon the ball 10^a (or inversely) the axis of the screw being substantially on a line tangent to the circumference and passing 55 through the axis of the balls 10^a, 10^b, 10^c, 10^d, etc.

60 The number and diameter of the balls is variable within wide limits, according to the use of the apparatus, as well as their distribution and disposition with reference to the surface to be pressed. For example, the balls 12, cooperating with the balls 11, need not be superposed upon the latter, but may be disposed in a concentric circular row either 65 in the interior or at the exterior, and herein

the pressure will be exercised radially, towards or from the centre, upon a cylindrical surface, for example. The intermediate balls or rollers may be replaced by other suitable connecting means. The surface to be pressed 70 is not necessarily circular, but may have any other form such as rectangular, and it may be either plane or curved (for example the above mentioned cylindrical surface).

The balls may be replaced by rollers of 75 suitable form, for instance of a tapered shape.

The apparatus may also be movable and for instance rotatable, as in the case of a 80 friction clutch.

By way of example, the following description relates to a coupling device for the rapid end-to-end coupling of the pipes employed for various operations such as pumping, irrigation, exhaustion or drainage, etc., and 85 chiefly for the coupling of fire hose.

90 In the form of construction shown in Figs. 3 to 5, the two pieces of hose 20—21 to be coupled are provided with the coupling ends 22—23, toothed in the known manner at 24 so that they may be properly secured to the hose, said coupling ends being flanged respectively at 16 and 17. The flange 16 is somewhat larger in diameter than the flange 17, and it carries a packing ring 2^a; said flange 16 is slidable lengthwise in a metallic 95 casing which consists of the members 6 and 3, screwed together by a thread 25 and holding between them a flat ring 7, thus forming with the inner end 6^a of the member 6 a circular recess or housing 9 containing balls 10 (or rollers) having the aforesaid disposition. 100

The member 3, which forms with the member 6 the said casing of the device, has a semi-circular flange 3^a which is open at 3^b for the insertion of the coupling member 23 which is slidable by means of its flanged end 17. 105

110 It should be observed that this connection known per se, is given solely by way of example, and it may be replaced by analogous means, and chiefly by a bayonet joint as shown in Figs. 6 and 7, and herein the flange 17 comprises tenons 1^a which may be engaged below the projections 3^a of the member 3 by 115 a suitable rotation.

The operation is as follows:

120 The screw 14 being unscrewed, the flange 16, upon which the casing 5—6 has been placed, is pushed towards the end 6^a so that the flange 17 of the member 23 may be inserted either laterally or by rotation, and when the said flange is in position, the screw 14 is screwed down. The wedge 13 separates the upper balls 10, and these, through the medium of the lower balls 12, press uniformly upon the flange 16 which is thus pressed upon the flange 17, maintained by the flanged parts 3^a. The device is made leakless by the packing 2^a. 125 130

The coupling is released by unscrewing the screw 14.

Figs. 8 and 9 show a modification in which the casing consists of two identical members 6-6^a which are assembled for instance by the tenons 26-26^a. Each member contains a respective set of balls 10-12, 10^a-12^a, adapted to bear against respective flanges (not shown) of the coupling members 22-23. The balls may be controlled as shown in Fig. 3, but it is possible to employ the arrangement shown in Fig. 8 in which the balls are separated by two cams 27-27^a which are keyed to respective axes 28-28^a provided with operating levers 29-29^a, said levers being respectively terminated by a hook 30-30^a by which they may be held in the position of pressure.

The pressure is exercised first upon one of the devices and then upon the other, and for the first device the movement is continued beyond the definite position, so that the lever can be moved aside to allow the second device to be operated. When the two levers are left free, they will return slightly to the rear and will be held fast by hooking together.

Obviously, the said invention is not limited to the forms of construction herein described and represented, which are given solely by way of example.

Having now described my invention what I claim as new and desire to secure by Letters Patent is:

1. A coupling device for the end-to-end coupling of two tubular members, comprising a cylindrical casing slidably mounted on the coupling end of one of said members, a portion of said casing having an inner diameter greater than the outer diameter of said coupling end and defining therewith an annular chamber, a second casing slidably mounted on the coupling end of the other tubular member and engaging a flange on said other member, means for securing together both casings, a plate provided with regularly spaced apart and circumferentially elongated apertures securely held between said casings and slidably mounted on the first mentioned coupling end, a plurality of rolling members disposed in said annular chamber between the end of the corresponding casing and the partition plate, some of said rolling members being adapted to pass through the apertures of said plate for bearing upon a flange of the corresponding coupling end, and means adapted to be operated at will for pressing together said rolling members, whereby the set out rolling members are axially displaced and both ends of the tubular members are pressed against each other.

2. In a pressure producing contrivance comprising balls arranged in a row within a housing the surfaces of which in contact with the balls allow the latter to roll and means for pressing the balls together, an ap-

ertured housing the apertures of which are elongated and of such a shape that but one ball can project at a time through one aperture beyond the external wall of the housing and be moved longitudinally of the row. 70

3. In a pressure producing contrivance as claimed in claim 2, a housing having equally spaced apertures.

4. In a pressure producing contrivance as claimed in claim 2, a ring-shaped housing for 75 the balls and apertures provided in the housing according to directions substantially perpendicular to the plane of the ring.

5. In a pressure producing contrivance comprising rolling members arranged in a 80 row within a housing the surfaces of which in contact with the rolling members allow the latter to roll and means for pressing the rolling members together, an apertured housing the apertures of which are elongated and 85 of such a shape that but one rolling member can project at a time through one aperture beyond the external wall of the housing and be moved longitudinally of the row.

6. A coupling device for the quick end-to-end coupling of two tubular members such as two sections of fire-hoses, comprising a casing slidably carried by one of said members, a flange at the coupling end of said member, a plurality of rolling members disposed in a 90 circular row within said casing shaped to form a rolling housing for said rolling members, said housing provided with regularly spaced apart and circumferentially elongated apertures through which some of the rolling members will project beyond the housing wall and bear on said flange, means for the quick end-to-end connection of said casing with the other tubular member and means adapted to be operated at will for pressing together said 95 rolling members, whereby the tubular members will be pressed together end-to-end. 100

7. A coupling device for the quick end-to-end coupling of two tubular members such as two sections of fire-hoses, comprising two casings respectively carried and slidably on said members, a flange at the coupling end of each member, a plurality of rolling members disposed in a circular row within each of said casings shaped to form a rolling housing for 105 said rolling members, said housing provided with regularly spaced apart and circumferentially elongated apertures through which some of the rolling members will project beyond the housing wall and bear on the adjacent flange, means for the quick end-to-end connection of said casings together and each casing provided with means adapted to be operated at will for pressing together the corresponding rolling members, whereby the 110 tubular members will be pressed together end-to-end. 115

8. A coupling device, as claimed in claim 7, wherein each casing is provided with manually operable means for pressing together 120

the rolling members, including a rotatable cam provided between two adjacent rolling members to press them apart and a hook rotatable with said cam and located outside the casing, both said hooks being located for mutual locking engagement in the clamping position.

In testimony whereof I have signed my name to this specification.
